A. H. SMITH & M. BLANCH.
CLEANING DEVICE.
APPLICATION FILED SEPT. 3, 1913.

1,227,682.

Patented May 29, 1917.

UNITED STATES PATENT OFFICE.

ARTHUR H. SMITH AND MALCOLM BLANCH, OF WORCESTER, MASSACHUSETTS, ASSIGNS TO DOMESTIC VACUUM CLEANER COMPANY, OF WORCESTER, MASSACHUSETTS, A CORPORATION OF MASSACHUSETTS.

CLEANING DEVICE.

1,227,682.

Specification of Letters Patent. Patented May 29, 1917.

Application filed September 3, 1913. Serial No. 788,026

To all whom it may concern:

Be it known that we, ARTHUR H. SMITH and MALCOLM BLANCH, citizens of the United States, residing at Worcester, in the county of Worcester and State of Massachusetts, have invented a new and useful Cleaning Device, of which the following is a specification.

This invention relates to a combined vacuum cleaner and brush sweeper and the principal objects thereof are to provide a simple, cheap and practicable construction in which the brush sweeper can be kept out of commission until after the suction cleaner has taken up the loose dust, thus preventing the raising of dust and rendering the device thoroughly efficient for all purposes, and extremely sanitary; to provide a brush cleaner that will occupy a minimum amount of space and will be so located with respect to the wheels for operating the pneumatic part of the cleaner that they will not interfere with the effective operation thereof, and yet will operate the brush with a high degree of efficiency. Also to provide an improved construction of frame for supporting the brush and its operating devices and improved means for adjusting and holding the frame so as to secure a maximum efficiency in the operation of the device.

The invention also involves improvements in details of construction as will appear hereinafter.

Reference is to be had to the accompanying drawings in which,

Fig. 1 is a side elevation of a combined pneumatic and sweeper cleaner constructed in accordance with this invention;

Fig. 2 is a longitudinal central sectional view of a portion of the same;

Fig. 3 is a plan of the brush supporting frame and connected parts; and

Fig. 4 is an end elevation showing the details of the means for holding the sweeper roller in position.

The invention is shown as applied to a well-known type of pneumatic cleaning device comprising a main casing 10, suction producing device or bellows 11, nozzle 12 at the front end of the casing, and rollers 13 at the rear end of the casing for supporting that end of the casing and operating the bellows through pitmen connections 14 or the like. As usual in this class of pneumatic

cleaners, the machine is operated by a handle 55 15 pivotally connected by a bail or the like 16 with the body of the casing, adapted to be held in vertical inoperative position by a clip 17 or the like. It is to be observed, however, that the bail is pivoted to the casing 60 itself in front of the operating wheels 13 and substantially on a level with the top thereof so that the pressure applied in pressing down on the handle in the usual way of operating will tend to swing the nozzle or 65 front end of the casing about the operating wheels as a center and keep the nozzle in proper contact with the surface to be cleaned.

The dust box 18 of the main casing 10 is 70 shown as recessed at the bottom and in this recess is fixed an auxiliary casing 20. This auxiliary casing is intended to be a permanent part of the device and while it can be removed for repairs, it is not intended to be 75 removed in the ordinary use of the machine. This casing is provided with a frame pivoted thereto by means of screws 21 or other pivots located between the nozzle 12 and the rollers 13 and in fact, substantially half way 80 between them. This frame comprises a pair of side arms 22 and a transverse rod 23. Adjacent to the two side arms are brackets 24 parallel with them and spaced therefrom. These are bent up at their ends and riveted 85 to the transverse rod 23. These parts 22, 23 and 24 are preferably formed of sheet metal die'd out into shape, as indicated in Fig. 3, the connection between one of the arms 22 and the rod 23 being doubled upon itself at 90 25 to provide a projecting handle for operating the frame from the side. Journalized between each piece 24 and the adjacent arm 22 is an operating roller 26 preferably covered with rubber or the like. Each of these 95 rollers is adapted to be engaged by a roll 27 fixed on the shaft 28 of a rotary brush 29.

For the purpose of securing an intimate contact between the rolls and the rollers, each arm 22 is provided with a spring 30 100 held between a pin 31 fixed to the arm, and a sheet metal support 32 slidably mounted on the arm and having on the inner side thereof a cylindrical projection 33 which extends into the end of the shaft 28 and 105 forms a journal therefor.

The shaft of the brush 29 passes through slots 34 in the auxiliary casing 20. The aux-

iliary casing is provided with a pair of dust pans 36 of a construction well known in the rotary brush type of carpet sweepers. They are operated by a pair of handles 37 in the usual way.

For the purpose of holding the rollers 26 firmly down in contact with the surface to be cleaned, a spring 40 is arranged to bear on the rod 23 and this motion is limited by 10 a stop 41 engaging the lower side of this rod 23. This spring and stop thus hold the frame in operative position. When it is desired to put the brush out of operation, the frame is pressed upwardly around its 15 pivots against the resistance of the spring 40 until it comes above the top of a spring latch 42 which then holds it in its elevated inoperative position.

It will be noticed that the brush is located 20 between the nozzle and the main operating rollers 13 but nearer the latter, and that the operating rollers 26 for the brush are located between the brush and the main operating rollers 13 so as to be as far from 25 the nozzle as is convenient. This arrangement with the auxiliary casing or brush sweeper at the rear of the bottom of the main casing results in securing a high degree of pressure on the rollers 26 from the 30 handle 15. On account of this arrangement of the parts, both sets of rollers are in position to receive sufficient pressure to insure their effective operation under all ordinary conditions. The adjustable roller 45 is used 35 to regulate the vertical position of the nozzle so that the device can be used effectively on different kinds of surfaces. It will be seen, also, that the rollers 26 are held firmly in a rigid frame and are supported thereby 40 at both ends so that there is no danger of getting out of true or wobbling on their axes.

By the adjustments specified, all desired 45 combinations of the pneumatic cleaner and sweeper can be obtained. That is to say, the two can be used together for the purpose of securing a maximum cleaning action, or when it is desired to use the pneumatic cleaner alone such resistance as is provided 50 by the brush sweeper can be eliminated by turning it up out of operative position. It will be understood that ordinarily the cleaner is pushed forward so that the nozzle passes over the surface to be cleaned, before 55 the brush; consequently the duty of the brush is merely to pick up threads, papers or other things which have escaped the action of the suction cleaner. It will be seen, therefore, that on account of the well known efficiency of the suction device itself, the brush 60 does not have a high duty to perform and consequently a comparatively small pair of pans for dust is sufficient. It has been found in practice that without materially taking away from the space occupied by the dust

box, a brush sweeper can be inserted in the position indicated in this application, of such a character as to perform this duty with an extremely high efficiency.

Although we have illustrated and described a specific form of the invention, we are aware of the fact that modifications can be made therein by any person skilled in the art without departing from the scope of the invention as expressed in the claims. Therefore we do not wish to be limited to all the details of construction herein shown and described, but

What we do claim is,—

1. The combination with a supporting frame, and rollers for supporting the end of the frame, of a complete brush sweeper located close to said rollers under the bottom of the frame, and comprising a rotary brush, rollers for operating the brush located between the brush and the first named rollers, and means for adjusting the brush rollers into and out of contact with the surface to be cleaned.

2. The combination with a main casing, 90 and rollers for supporting one end thereof, of an auxiliary casing located under said main casing near said rollers, a brush carried by said auxiliary casing, a roll on each end of the brush, and a pair of rollers supported from said auxiliary casing between the brush and first named rollers, and adapted to engage the surface to be cleaned and also to engage said rolls, for the purpose of operating the brush.

3. The combination with a casing having a support at one end and supporting rollers at the other, of a frame pivoted on the bottom of said casing between the support and rollers and having its free end adjacent to said rollers, a second pair of rollers journaled on said frame, a brush operated by said second pair of rollers, and means for holding the free end of said frame in two positions to adjust the height of the second pair of rollers and brush.

4. The combination with a casing having a support, and rollers arranged at opposite ends, of a frame pivoted transversely between the support and rollers, means for holding the free end of said frame in two positions at different elevations, a brush carried by said frame and having rolls thereon, a pair of rollers journaled on said frame for operating the rolls and brush, and springs 120 on the frame for holding said rolls yieldingly in contact with the rollers.

5. The combination of a frame comprising a pair of side arms, a transverse rod connecting the ends of said arms, a pair of longitudinal pieces parallel with said arms and spaced from them connected with said transverse rod at one end and with the arms at the other end, said pieces and arms having journals thereon, a pair of rollers, one 130

- journalized between each of said pieces and the adjacent arm, a brush carried by said frame, and means for driving said brush from the rollers.
5. In a carpet cleaner, the combination of a support, a sweeper casing on the bottom thereof, a movable frame, a brush, a roller carried by said frame for operating the brush, a stop, and yielding means for holding said frame down in contact with said stop.
10. 6. In a carpet cleaner, the combination of a support, a sweeper casing on the bottom thereof, a movable frame, a brush, a roller carried by said frame for operating the brush, a stop, and yielding means for holding said frame down in contact with said stop.
15. 7. In a carpet cleaner, the combination of a support, a movable frame, a brush, a roller carried by said frame for operating the brush, yielding means for holding said frame down, and positive means for holding the frame up in opposition to said yielding means, said positive means being detachably connected with the frame.
20. 8. In a carpet cleaner, the combination of a movable frame comprising a pair of side arms, a roller carried by each arm for engaging the surface to be cleaned, a support slidably mounted on each arm, yield-
- ing means for moving each support toward one of the rollers, a brush shaft carried by said supports, and a pair of rolls fixed on said shaft engaging said rollers.
9. In a carpet cleaner, the combination of a movable frame comprising a pair of side arms, a roller carried by each arm for engaging the surface to be cleaned, a sheet metal support slidably mounted on each arm, a spring on each arm for moving the support toward one of the rollers, a projection extending from each support inwardly, a shaft supported at its ends on said projections and having a brush thereon, and a pair of rolls fixed on said shaft and operated by the rollers.
40. In testimony whereof we have hereunto set our hands, in the presence of two subscribing witnesses.

ARTHUR H. SMITH.
MALCOLM BLANCH.
